TRAILER HOOK-UP MIRROR

Robert J. Strohmeier, Castle Rock, Colo., assignor to R. J. Strohmeier Co., Castle Rock, Colo.

Filed Mar. 23, 1971, Ser. No. 127,439

Term of patent 14 years

Int. Cl. D12—16

U.S. Cl. D14—6

FIG. 1 is a perspective view looking down and to the left upon the trailer hook-up mirror of the present invention;

FIG. 2 is a side elevation thereof;

FIG. 3 is a front elevation;

FIG. 4 is a rear elevation;

FIG. 5 is a top plan view; and

FIG. 6 is a bottom plan view.

The side opposite the side shown in FIG. 2 is a mirror image thereof.

I claim:

The ornamental design for a trailer hook-up mirror, as shown and described.
